UNITED STATES PATENT OFFICE.

GEORGE E. STEVENSON, OF INDIANAPOLIS, INDIANA.

ARTICULATED DOOR.

Application filed July 11, 1924. Serial No. 725,528.

The object of my invention is to produce a door of the roll curtain type, and means by which the same may be either manually or mechanically manipulated. The accompanying drawings illustrate my invention.

Fig. 1 is a perspective of a door opening equipped with my improved door; Fig. 2 an elevation in a partial vertical section of the construction with the door opening 10 closed; Fig. 3 a horizontal section on a larger scale on line 3—3 of Fig. 2; Fig. 4 a vertical section on line 4—4 of Fig. 3; Fig. 5 a vertical section on line 5—5 of Fig. 4; Fig. 6 a vertical fragmentary section, on an 15 enlarged scale, at the upper right hand corner of Fig. 2; Fig. 7 a fragmentary perspective section on the articulated closure; Fig. 8 a fragmentary horizontal section of a suitable belt or chain forming part of 20 the closure; Fig. 9 a horizontal section, on an enlarged scale, on line 9—9 of Fig. 2; Fig. 10 a vertical section on line 10—10 of Fig. 9, and Fig. 11 a vertical section, on an 25 enlarged scale, on line 11—11 of Fig. 10.

In the drawings 15 indicates the opening to be closed and flanked at the sides by casings 16 and 17; at the top by casing 18, and at the bottom by groove 20.

Mounted in casing 16 is a shaft 21 provided at top and bottom with drums 22, 22 to each of which is secured one end of a chain 23 formed of suitable links so that they may be wrapped around drums 22. Mounted in casing 17 is a vertical shaft 24 carrying 30 a drum 25 preferably of the same diameter as drums 22, the opposite end of chain 23 being attached thereto. While the links forming chains 23 may be of uniform length, they may conveniently be of graduated 35 lengths as clearly indicated in Fig. 9, the arrangement being such that they may thus be more readily wrapped in several layers around drums 22 and 25.

Each link of chain 23 carries a plate 26 40 to which may be secured either a door-forming slat 27 extending from one chain to the other, or a short block 28 arranged to fill groove 20, the slats 27 and blocks 28 being articulated, as indicated in Fig. 7, 45 or in any other suitable manner, so that the slats 27 will form a suitable closure for slot 20, and blocks 28 will form a suitable filler for slot 20 when slats 27 are retracted from opening 15. As it is not 50 feasible in most instances to provide drums of a sufficient diameter to accommodate, in

a single layer, all of the slats 27 necessary to close opening 15, it is necessary to provide some means for permitting adjustment of the distance between the axes of drums 60 22 and 25 and for this purpose the shaft 24 is mounted, top and bottom, in sliding blocks 30 which are normally urged away from shaft 21 by springs 31, the arrangement being such as to keep chains 23 taut 65 at all times.

It is desirable that a door of this type be mechanically manipulated, and for that reason I provide an electric motor 40 connected by a suitable gear train 41 with shaft 70 21 and, in order that the movement of the chains 23 may at all times be the result of pull, rather than a push, shaft 21 is connected with shaft 24 by a cross shaft 42 and pairs of meshing bevel gears 43 and 44, 75 the gear 43 which is mounted on shaft 42 being splined thereon and associated with the adjacent block 30 in such manner as to partake of all of the lateral movements of shaft 24 under the action of springs 31. 80

Motor 40 is controlled by suitable reversing switch 50 having a controlling arm 51 extended for manual manipulation through casing 16 and also extended so as to be engaged by pins 52 and 53 (Fig. 9) carried 85 by one of chains 23, the arrangement being such that said pins will carry the switch to neutral position at appropriate times when the opening 15 is either opened or closed. 90

In view of the possibility of disarrangement of the mechanical operating means, it is desirable that manual operating means be provided and for that purpose I provide a hand wheel 60 carried by shaft 61 provided at its inner end with clutch 62 adapted to be moved into or out of connection with a clutch element 63 carried by the shaft of the motor, the arrangement being such that, by shifting shaft 61 axially, the 100 hand wheel may be made effective or ineffective to drive shafts 21 and 24, and shaft 61 may be readily retained in either one of its positions by suitable spring retainer 65 of a well known type. Guides 66 are arranged at the top and bottom of opening 15 for chain 23. 105

I claim as my invention:

1. A door comprising a pair of parallel winding drums, two chains forming driving 110 connections between the drums, door-forming slats connecting from links of one chain

with links of the other chain, and means, winding drums, two chains extending from by which one of said drums may be rotated, one drum to the other, door-forming slots

2. A door comprising a pair of parallel winding drums, two chains extending from of the other chain, means by which the 30 one drum to the other, door-forming slats of the other chain, means by which the 30 extending from links of one chain to links drums may be simultaneously rotated, means of the other chain, a series of filler blocks for supporting one drum for a lateral move- of the other chain, a series of filler blocks 35 carried by the lower chain, adjacent one end movement, and means for yieldingly urging said drum laterally away from the other drum carried by the lower chain, adjacent one end slat, and means by which one of said drums to keep the chains taut.

10 may be rotated.

3. A door comprising a pair of parallel winding drums, two chains extending from of the other chain, a series of filler blocks 40 winding drums, two chains forming driving one drum to the other, door-forming slats connections between the drums, door-form- extending from links of one chain to links of the other chain, a series of filler blocks 40 ing slats connecting from links of one chain carried by the other chain, adjacent one end with links of the other chain, and means by which the drums may be simultaneously rotated, means for support- rotated.

4. A door comprising a pair of parallel winding drums, two chains extending from of the other chain, a series of filler blocks 45 one drum to the other, door-forming slats ally away from the other drum to keep the extending from links of one chain to links chains taut.

20 of the other chain, a series of filler blocks. In witness whereof, I have hereunto set my carried by the other chain adjacent one end hand at Indianapolis, Indiana, this 7th day of July, A. D. one thousand nine hundred 50 slat, and means by which the drums may be simultaneously rotated, and twenty four.

25 5. A door comprising a pair of parallel

GEORGE E. STEVENSON.

Certificate of Correction.

It is hereby certified that in Letters Patent No. 1,585,270, granted May 18, 1926, upon the application of George E. Stevenson, of Indianapolis, Indiana, for an improvement in "Articulated Doors," errors appear in the printed specification requiring correction as follows: Page 1, line 112, claim 1, and page 2, line 14, claim 3, strike out the word "from"; and that the said Letters Patent should be read with these corrections therein that the same may conform to the record of the case in the Patent Office.

Signed and sealed this 22d day of June, A. D. 1926.

[SEAL.]

M. J. MOORE,
Acting Commissioner of Patents.
